UNITED STATES PATENT OFFICE.

CLARA A. McDOWELL, OF REDONDO BEACH, CALIFORNIA.

IRONING-BOARD LACE.

1,254,614.

Specification of Letters Patent.

Patented Jan. 22, 1918.

Application filed May 8, 1917. Serial No. 167,267.

To all whom it may concern:

Be it known that I, CLARA A. McDOWELL, a citizen of the United States, residing at Redondo Beach, in the county of Los Angeles and States of California, have invented new and useful Improvements in Ironing-Board Laces, of which the following is a specification.

This invention relates to lacing devices especially adapted to be applied to ironing boards for holding a spread in proper position thereon and it consists in the novel features hereinafter described and claimed.

An object of the invention is to provide a lacing device of simple and durable structure which may be easily and quickly applied to an ironing board or removed therefrom and which when in position will hold the spread properly stretched over the surface of the board.

In the accompanying drawing:—

Figure 1 is a plan view of an ironing board showing a spread applied thereto with the lace device holding the same in position; Fig. 2 is an inverted plan view of the lace device;

Fig. 3 is a similar view of the lace device detached.

The device comprises strips 1 of fabric material preferably canvas which are provided at their inner edges with eyelets 2. Hooks 3 are applied to the outer portions of the strips 1 and are adapted to be connected with the edge portions of a spread 4. The said spread lies over the upper portion of the ironing board and its edges are carried around the edges of the same and the said hooks 3 are engaged with those edge portions of the spread 4 which are disposed under the board.

Lacing cords 5 are threaded through the eyelet 2 in a usual manner whereby the inner edge portions of the strips 1 are connected together as best shown in Fig. 2 of the drawings. Bar pins 6 are provided at their sides with eyes 7 and the cords 5 from the end or terminal eyelets 2 of the strips 1 are threaded through the eyes 7 of the pins 6 and are then carried back through the said end or terminal eyelet and the adjacent ends of the cords 5 are tied together. When the lace device is applied the portions of the cords 5 which extend beyond the ends of the strips 1 are carried around the ends of the ironing board as best shown in Fig. 1

and the bar pins 6 are engaged with the portions of the spread 4 which lie in the vicinity of the ends of the ironing board. Consequently when the cords 5 are tightened before they are tied together, they not only draw the strips 1 toward each other but they also draw the bar pins 6 toward the ends of the ironing board and hence the spread 4 is effectually stretched over the ironing board and is in condition to receive the articles of clothing to be pressed.

From the foregoing description taken in conjunction with the accompanying drawing, it will be seen that an ironing board lace device of simple and durable structure is provided and that the same may be easily and quickly manipulated to effectually stretch a spread over the surface of an ironing board and hold the same in proper position thereon.

Having described the invention what is claimed is:—

1. A lace device especially adapted to be applied to the spread of an ironing board comprising strips of fabric provided at their inner edges with eyelets, hooks carried at the outer edges of the said strips and adapted to engage the edge portions of the spread, lace cords threaded through the eyelets, bar pins provided at their sides with eyes, the end portions of the said lace cord being carried through the said eyes and then extended back through the terminal eyelets of the strips and adapted to be tied together.

2. A lace device especially adapted to be used for holding a spread in position upon an ironing board comprising fabric strips, eyelets applied to the inner edges of the said strips, hooks applied to the outer edges of the said strips and adapted to engage the spread of the ironing board, cords threaded through the said eyelet and crossing each other and connecting the strips together, bar pins provided at their sides with eyes, the end portions of the said cords being threaded through the said eyes, said bar pins adapted to be secured to the edges of the spread above the surface of the ironing board, the said end portions of the said cords from the said bar pins being carried back and threaded through the end eyelet and adapted to be tied together.

In testimony whereof I affix my signature.

CLARA A. McDOWELL.
